UNITED STATES PATENT OFFICE

147,140

DESIGN FOR A BRUSH OR SIMILAR ARTICLE

Valborg A. Nordeng, Shelly, Minn.

Application April 12, 1946, Serial No. 128,526

Term of patent 7 years

(Cl. D9—2)

To all whom it may concern:

Be it known that I, Valborg A. Nordeng, a citizen of the United States, residing at Shelly, in the county of Norman and State of Minnesota, have invented a new, original, and ornamental Design for a Brush or Similar Article, of which the following is a specification, reference being had to the accompanying drawing, forming part thereof.

Figure 1 is a side elevational view of a brush or similar article, showing my new design, and

I claim:

The ornamental design for a brush or similar article, as shown.

VALBORG A. NORDENG.
